His Attorney.

UNITED STATES PATENT OFFICE

2,347,989

ELECTRIC APPARATUS

Locke H. Burnham, Pittsfield, Mass., assignor to
 General Electric Company, a corporation of
 New York

Application December 28, 1942, Serial No. 470,341

2 Claims. (Cl. 257—191)

My invention relates to an electric apparatus, and to an improved integral cooling unit to be attached to the casing of the apparatus.

Heretofore it has been customary in the manufacture of electric induction apparatus such as transformers and reactors to provide an enclosing casing filled with a dielectric fluid such as oil, and allow the oil to circulate through a plurality of groups of tubes which are disposed around the transformer casing. Constructions have also been suggested which include a cooling unit separately mounted on a base and connected to the apparatus casing through which a cooling fluid may be forced such as by providing a pump in the piping connecting the cooler to the casing.

It is therefore an object of my invention to provide an electric apparatus with an improved cooling unit which may be removably and simply attached to the transformer casing.

Another object of my invention is to provide an improved integral cooler construction including a pump attached to the cooler unit which may be simply and removably attached to a casing of an electric induction apparatus.

Further objects and advantages of my invention will become apparent from the following description referring to the accompanying drawing, and the features of novelty which characterize my invention will be pointed out with particularity in the claims annexed to and forming a part of this specification.

In the drawing Fig. 1 is a sectional side elevation of an electric induction apparatus which is provided with an embodiment of my invention; Fig. 2 is a sectional side elevation of an electric induction apparatus provided with a modification of my invention, and Fig. 3 illustrates a modification of the construction illustrated in Fig. 1.

In the drawing I have illustrated an electric induction apparatus including a conventional core 10 surrounded by a plurality of windings 11. The windings are separated so as to provide a duct 12 through which a suitable dielectric and cooling fluid may circulate. The core and coils are enclosed in a suitable casing 13 which is filled with a suitable cooling fluid such as oil to any suitable level such as that indicated by the numeral 14. In order to provide an arrangement for cooling the dielectric fluid I provide a cooler construction 15. This construction may have any suitable shape and includes a box shape having inner and outer sides 16 and 17, a top 18 and a bottom 19. The transformer tank is provided with openings 20 and 21 near the top and bottom thereof and the cooling unit is provided with similar openings 55

22 and 23 which are in substantial registry with the openings in the transformer casing. The integral unit 15 may be suitably attached to the side of the casing having the openings 20 and 21 in any suitable manner such as by brazing, welding or bolting at the adjacent surfaces as is indicated by the numeral 24.

In order to force the circulation of the fluid out the top opening 20 and into the unit I provide a pump 25 having an impeller 26. A partition 27 is provided adjacent the impeller 26 having an opening 28 to facilitate the forcing of the oil out the opening 20 down through the cooling unit and back into the transformer casing through the opening 21. In order that the cooling fluid may circulate through the duct 12 in the coils instead of between the outer surface of the coils and the casing, a baffle 30 may be provided. In order to provide supplementary means for cooling the circulating dielectric fluid I provide a suitable coil 31 through which a suitable cooling fluid may circulate, such as water. Any suitable number of coils 31 may be provided and the bottom ends 32 thereof may be attached to a suitable header construction which is provided by a partition 33 which may be welded to the bottom end of the cooling unit 15. A suitable pipe 34 may be provided which is connected to the bottom of the side 17 of the cooler which connects with a chamber 35 which forms a header for the plurality of cooling coils 31. The opposite ends of the cooling coils may extend through apertures 36 in the casing 13 which apertures are surrounded by a box shaped member 37 which is welded to the side 17 so as to provide a suitable header construction for the top ends of the cooling coil 31.

In the arrangement illustrated in Fig. 2 I have shown a similar transformer casing construction 13 having an integral pump and cooler unit 40. The cooler construction includes inner and outer sides 41 and 42 having a bottom 43 and a top 44. A passage 45 at the top connects with a suitable passage 46 at the top of the casing 13 and the bottom of the cooler is provided with a suitable passage 47 which connects with an opening 48 in the casing 13. This cooler may be removably attached to the casing 13 in any suitable manner such as by bolting as is indicated by the bolt 49. In order to provide an arrangement for cooling the circulating dielectric fluid a plurality of pipes 50 are provided in the cooler which are open at the bottom as indicated by the numeral 51. The tops of the pipes are connected with a header 52 which in turn connects with the atmosphere through an opening 53. In order to provide a

single pump construction for pumping both the oil and the air, I provide a pump motor 55 having an oil impeller 56 and an air impeller 57. The oil will be pumped through openings 58 and 59 and by the injection principle will cause oil to also flow through the passage 60. Furthermore the air will be sucked in through the openings 51 of the tube and out through the openings 53 at the top.

In the construction illustrated in Fig. 3 I have provided a box shaped cooler 61 which is suitably attached to a side 62 of the transformer casing. It will be seen that the cooler is provided with an outside surface 63, a top 64 and a bottom 65. Vertical sides of course which are not shown are provided. The unit is then bolted to the side 62 so that the side of the transformer provides an inner side for the cooling unit. Openings 66 and 67 are provided at the top and bottom of the side 62 and a pump 68 is provided which is attached to the top of the cooling unit, the pump having an impeller 69. A baffle 70 is provided having an opening 71 through which a portion of the oil is circulated. It will be noted that the baffle ends close to the outer edge 63 of the cooling unit so as to provide an injection principle for circulation of the oil through the opening 66 and out the opening 67 at the bottom of the cooler. A cooling coil 72 through which any suitable cooling liquid such as oil may circulate is provided.

Although I have shown and described particular embodiments of my invention, I do not desire to be limited to the particular embodiments de-

scribed, and I intend in the appended claims to cover all modifications which do not depart from the spirit and scope of my invention.

What I claim as new and desire to secure by Letters Patent of the United States is:

1. An electric induction apparatus including an enclosing casing, a dielectric fluid within said casing, a cooling unit, said casing and cooling unit having openings in substantial registry so

10 that said fluid may circulate between said casing and cooling unit, passage means within said cooling unit through which a cooling fluid may pass, partition means integral with the walls of said cooling unit at one end to form a header for said passage means, and pump means mounted on said cooling unit for forcing said fluid from said casing through said unit and back to said casing, said cooling unit and pump means being removable as a unit from said casing.

15 2. An electric induction apparatus including an enclosing casing, a dielectric fluid within said casing, a cooling unit having one face open, passage means within said cooling unit through which a cooling fluid may pass, means for mounting said cooling unit tightly to a side of said casing so that said side closes said open face of said cooler, said side having spaced openings so that said dielectric fluid may circulate through said cooler and around said passage means, and pump means mounted on said cooling unit for forcing said dielectric fluid from said casing through said unit and back to said casing through said openings.

LOCKE H. BURNHAM.
